ELECTRIC DISCHARGE DEVICE CIRCUIT

Willem F. Westendorp, Schenectady, N. Y., assignor to General Electric Company, a corporation of New York

Application July 21, 1934, Serial No. 736,362

9 Claims. (Cl. 176—124)

My invention relates to operating circuits for electric discharge devices, and in particular for lamps containing thermionic cathodes.

One object of my invention is to provide an improved circuit for electric discharge devices for preheating the cathode before applying operating potential across the electrodes.

Another object of my invention is to provide a circuit for electric discharge devices which will segregate currents of two different characteristics in such manner that in one case the cathodes of the devices are heated alone, and in the second case the devices are energized and the cathodes are heated.

For a better understanding of my invention, together with other and further objects thereof, reference is had to the following description, taken in connection with the accompanying drawing, and its scope will be pointed out in the appended claims.

In the accompanying drawing, Fig. 1 illustrates diagrammatically a circuit for electric discharge devices which are in this case lamps in accordance with my invention, and Figs. 2, 3 and 4 illustrate diagrammatically modifications of my invention.

Referring to Fig. 1 in detail, 4 and 5 are electric discharge lamps preferably of the type having a container provided with a rare gas and a vaporizable metal, such as sodium, for example. Lamp 4 comprises a container 8 an anode 6 and a cathode 7. The cathode 7 is of the unipotential type having a heater comprising a metal filament 9 attached at one end to the cathode surface, the other end being provided with a conductor sealed into the wall of the container 8. Lamp 5 is provided with an anode 10, a cathode 11, a heater 12 and a container 13. The end of the heater 9 projecting through the wall of the container 8 is in accordance with my invention connected to the anode 6 by conductor 14 and the corresponding end of heater 12 is connected by conductor 15 to the anode 10. The cathode 7 is connected to anode 10 by a conductor 16 and the cathode 11 may be similarly connected to a following lamp in a series circuit. It is illustrated, however, as being connected to a conductor 17 terminating in contacts 18 and 19. The anode 6 is connected by a conductor 20 to a contact 21, which, together with the previously mentioned contacts 18 and 19, comprise the stationary contacts for a reversing switch 22. The reversing switch comprises pivoted blades 23 and 24 connected respectively to the terminals of a direct current generator 25 by conductors 26 and 27. Film cut-outs 28 and 29 are respectively connected in shunt to the lamps 4 and 5 and are arranged to pass current when the lamps break or otherwise become inoperative.

In operating devices, connected in the above-

described circuits in accordance with my invention, the switch 22 is thrown to its lower position so as to apply a negative potential to the anode 6 and consequently to the succeeding anode 10. With the switch in this lower position, the circuit may be traced from the negative terminal of generator 25, conductor 26, switch blade 23, contact 21, conductors 20 and 14, heater 9, cathode 7, conductors 16 and 15, heater 12, cathode 11, conductor 17, contact 18, switch blade 24, conductor 27 to the positive terminal of the generator 25. A negative potential is thereby applied to both anodes 6 and 10 and because of the inherent characteristic of discharge devices for normally passing current only when positive potential is applied to the respective anodes, no current will flow across the discharge paths in the two lamps illustrated. The cathode surfaces 7 and 11 will, however, be heated by the current flowing through the heaters 9 and 12 which are connected in series across the generator.

In the operation of this type of lamp it is desirable to preheat the cathodes before applying the operating potential across the discharge path of the lamp, that is, from anode to cathode. If the operating potential is applied before the cathode is given a chance to become heated to its proper operating temperature, a sputtering of the electrode material takes place and metal is deposited on the glass envelope of the lamp with a consequent reduction in the light emission of this envelope and a reduction in the life of the lamp.

When the cathodes have been heated by passing current, as above described, the reversing switch 22 is operated to its upper position. In this position of the switch positive potential is applied to the anodes 6 and 10 of the lamps and consequently current will flow from the anode to cathode. Simultaneously current will also flow through the filament heaters 9 and 12 so that with this connection of the generator to the circuit, the lamps or, in other words their discharge paths, operate in multiple with the cathode heaters. The circuit in this instance may be traced from the positive terminal of generator 25 through conductor 27, switch blade 24, contact 21 and conductor 20 to anode 6. Current there flows through the vapor and gases in the envelope 8 to the cathode 7. Simultaneously, current flows through conductor 14 to heater 9 and to the cathode 7. Both currents from cathode 7 flow through conductor 16 to anode 10 and through conductor 15 to heater 12, across the discharge path from anode 10 to cathode 11, from cathode 11 through conductor 17 to contact 19, switch blade 23, conductor 26 to the negative terminal of generator 25. With this improved circuit, it is, therefore, possible to preheat the cathodes without applying an operating poten-

tial to the lamps, and by simply reversing the connections to the source, the lamps and the cathode heaters are operated simultaneously.

In Fig. 2 I have illustrated a modification of my invention in which the cathode heaters and the discharge paths of the respective lamps are operated in series with each other instead of in multiple, as shown in Fig. 1. The circuit in Fig. 2 is generally the same as that in Fig. 1, except that a unidirectional connection is applied between the cathode and the anode of each lamp. Referring to this figure, the direct current generator 25 and reversing switch 22 are connected as in Fig. 1. A rectifier 30 is connected between the conductor 20, leading to anode 6, and cathode 7. The rectifier passes current only in one direction, and this direction is opposite to the normal current flow between anode 6 and cathode 7. When switch 22 is in its lower position, in this connection, therefore, current will flow from the positive terminal of generator 25 through conductor 21, switch blade 24, contact 18, conductor 17 to heater 12. From this heater, current will flow to cathode 11 and through a conductor 31 to a rectifier 32, similar to the rectifier 30, to conductor 16, heater 9, cathode 7, conductor 33 to rectifier 30, conductor 20, contact 21, switch blade 23 and through conductor 26 to the negative side of the generator. The filament heaters 9 and 12 are, therefore, connected in series with each other and current will not flow between the cathodes and the anodes, since the positive potential is applied to the cathode. When the switch 22 is thrown to its upper position, however, positive potential is applied to the conductor 20 and anode 6. Current cannot flow through rectifier 30, since this unidirectional device is arranged to permit current to flow only in the opposite direction. It acts, therefore, as an insulator and the only path open for current to flow is from anode 6 to cathode 7 and then through heater 9, conductor 16 to anode 10. The rectifier 32 is also arranged to pass current in the opposite direction and current cannot, therefore, flow through it to the cathode 11 and the only path open for the current to flow is the discharge path from anode 10 to cathode 11. The current in this case may, therefore, be traced from the positive terminal to generator 25 through conductor 27, switch blade 24, contact 21, conductor 20, anode 6, cathode 7, heater 9, conductor 16, anode 10, cathode 11, heater 12, conductor 17, contact 19, switch blade 23, conductor 26 to the negative side of generator 25. This connection again provides for a permanent connection of each lamp and its rectifier and it is only necessary to reverse the connection at the source to obtain the above-described proper operation.

In Fig. 3 I have shown a second modification of my invention in which an alternating current generator 35 is used. In this combination a switch 36 may be operated to connect the lamps to the source either through a transformer 37 or through a rectifier 38. The cathodes in this arrangement are illustrated as filaments excited through transformers. When the switch is in position to connect the lamp circuit to the source through the transformer, the cathode or filament transformers are energized by a pulsating current obtained in a manner hereinafter explained and when the switch is thrown to connect the lamp circuit to the source through the rectifier, the lamps are energized by a pulsating direct current and the filaments are correspondingly energized by currents excited in the secondaries by

this pulsating current flowing through the primaries of the cathode transformers.

Referring to Fig. 3 in detail, lamps 40 and 41 are provided respectively with anodes 42 and 43 and filamentary cathodes 44 and 45. The cathode 44 is connected to the secondary 46 of a filament transformer and cathode 45 is connected to winding 47 of a filament transformer. A rectifier 48 is connected between the anode 42 and the midpoint of transformer winding 46, and a rectifier 49 is connected between anode 43 and the midpoint of transformer winding 47. The secondary winding 46 is energized by current flowing in primary winding 51 and the winding 47 is energized by current flowing in primary winding 52. When switch 36 is thrown to its lower position, current will flow from generator 35 through transformer 37 to the switch 36, which is provided with two blades 53 and 54. From blade 54, current flows through conductor 20 55, primary winding 52, conductor 56 through rectifier 49, conductor 57, primary winding 51, conductor 58, rectifier 48, conductor 59, switch blade 53 to transformer winding 37. The rectifiers 48 and 49 are arranged to pass only one- 25 half wave of the alternating current furnished by transformer 37. This is the negative half wave. The positive half-wave is impressed upon the anodes 42 and 43, but these half waves are of a low voltage and will not injure the lamp and the 30 cathodes are sufficiently heated by the other half wave. When switch 36 is thrown to its upper position, a pulsating direct current will be applied to the circuit in such manner that the positive terminal will be connected to switch 35 blade 53. Current will then flow from rectifier 38 to switch blade 53, conductor 59, to anode 42, cathode 44, winding 46, conductor 58 and winding 51, one end of which is connected to conductor 58. Generally it is attempted to smooth 40 out the output current of a rectifier by placing inductances in series therewith. In the present case this pulsating characteristic is taken advantage of and in some instances aggravated to excite the windings 46 and 47 and thereby generate 45 sufficient heat in addition to that caused by the discharge current, to properly heat the cathodes 44 and 45. The rectifiers 48 and 49 do not pass current in this case. From winding 51 current flows to conductor 57, anode 43, cathode 45, 50 winding 47, conductor 56, winding 52, conductor 55, switch blade 54 to the negative side of the rectifier 38.

In Fig. 4 I have shown a slight modification of Fig. 1 in which the switch 22 is not used as a 55 reversing switch but merely to include or exclude a shunt resistance from the circuit. When the switch is in its lower or preheating position the switch blade 23 engages contacts 60 and 61 connected to the conductor 20 and to one end of a 60 resistor 62 respectively. The switch blade 24 engages contacts 63 and 64. The contact 63 is connected to the conductor 17 and the contact 64 is connected to the other end of resistor 62. In this position of the switch the resistance 62 65 lowers the current in the series circuit due to the constant current in the generator circuit and consequently the potential across each lamp. The lowered potential is substantially equal to the operating potential of the lamps and is, 70 therefore, sufficient to force the proper heating current through the cathodes. When switch 22 is moved to its upper position, the potential across the lamps is raised momentarily, the discharge is started and the current then flows 75

through the cathode and discharge path in multiple.

Although I have described my invention as applied to lamps, it will be apparent to those skilled in the art that it is equally applicable to other electric discharge devices, such as rectifiers for example.

Furthermore, the lamps indicated in the accompanying drawing may be either the cathode glow type of lamp or they may be the positive column type of lamp. The invention is applicable to all discharge devices wherein it is desired to heat the cathodes before passing discharge current from anode to cathode.

15 What I claim as new and desire to secure by Letters Patent in the United States is:

1. In combination, a plurality of series connected electric discharge devices, each device being provided with an anode, a thermionic cathode spaced therefrom, and a heating circuit for said cathode connected in shunt to said spaced electrodes, a current source, electrical connections for said series circuit to said source so as to provide a current of predetermined characteristic to heat only said cathodes in series, and means for thereafter changing said connection to provide current of another characteristic for simultaneously causing a discharge between said electrodes and for heating said cathodes.

30 2. In a lighting circuit, the combination of a direct current source, a plurality of electric discharge lamps, each having an anode and a thermionic cathode, a connection from each cathode to the anode of the following lamp, a conductive connection between each anode and its corresponding cathode, means for connecting said lamps to said source so as to cause a current flow in a direction opposite to the normal flow of current between the electrodes of each lamp for preheating the cathodes, and means for thereafter changing the direction of the current flow so as to cause a discharge between said electrodes and for heating said cathodes.

45 3. In combination, a direct current source, a plurality of electric discharge devices, each provided with an anode, a cathode spaced therefrom, an envelope containing a rare gas and a conductive connection between said anode and one end of said cathode, a conductive connection between the other end of each cathode and the anode of the following lamp whereby said cathodes are connected in series, a reversing switch for applying a negative potential to said anodes whereby the cathodes are heated and for subsequently reversing said potential whereby a discharge current flows between said spaced electrodes respectively and through the cathodes in multiple with said discharge current.

60 4. In a lighting circuit, the combination of a direct current source, an electric discharge lamp provided with an anode, a cathode spaced therefrom and a unidirectional device connected in multiple to said electrodes and arranged to permit current flow in a direction opposite to the normal current flow between said anode and cathode, a reversing switch for applying current to said lamp from said source in a direction opposite to the normal current flow whereby the cathode alone is heated and for thereafter reversing said current to cause a discharge current to flow between said electrodes and cathode in series.

65 5. In a lighting circuit, the combination of a plurality of electric discharge lamps, each lamp being provided with an anode and a thermionic

cathode, a rectifier connected between the anode and one end of said cathode for passing current in a direction opposite to the normal current flow between said anode and cathode, a connection between the other end of said cathode and the anode of the following lamp, a direct current source, a reversing switch for connecting said source to said circuits and for subsequently reversing the connection whereby the cathodes are first energized in series with each other through said rectifiers and subsequently upon reversal of the current are energized by the current flowing across the discharge path from said anode to cathode and through the cathode to the anode of the following lamp.

15

6. In a lighting circuit, the combination of a plurality of electric discharge lamps, each being provided with an anode, a thermionic cathode and a unidirectional connection between anode and cathode for passing current in a direction opposite to the normal current flow from anode to cathode within the lamp, a connection from each cathode to the anode of the following lamp, a source of alternating current and a source of pulsating direct current, means for connecting said alternating circuit to said lamps for energizing the cathodes, and means for thereafter connecting the pulsating direct current source to said circuit for energizing both the cathodes and the anode to cathode circuits.

30

7. In a lighting circuit, the combination of a plurality of series connected electric discharge lamps, each lamp being provided with an anode, a cathode and a heater for said cathode, a connection including said heater in shunt to said electrodes, a current source, means for connecting said series circuit to said source so as to provide a current of predetermined characteristic to energize said cathode heaters in series, and means for thereafter changing said connection so as to provide current of another characteristic for causing a discharge current to flow between said electrodes and through said cathodes in multiple.

35

8. In combination, a plurality of series connected electric discharge devices, each device being provided with an anode, a thermionic filamentary cathode spaced therefrom and a conductive connection including said cathode in shunt to said spaced electrodes, a current source, means for connecting said circuit to said source and applying a potential which is below the breakdown potential across the electrodes in each device whereby current will flow through said cathodes and for subsequently increasing said potential to the breakdown potential of said devices whereby a discharge current will flow in said devices in multiple with the current flowing through said cathodes.

45

9. In combination, a plurality of series connected electric discharge devices, each device being provided with an anode, a cathode and a heater for said cathode, a connection including said heater in shunt to said electrodes, a current source, means for connecting said series circuit to said source and applying a potential which is below the breakdown potential between the electrodes of said devices whereby the said heaters alone are energized and for subsequently increasing said potential to the breakdown potential of said devices whereby a discharge current is caused to flow between said electrodes in multiple with the current flowing through said heaters.
